UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GUIDE-BOX FOR ROLLING-MILLS.

1,010,584.

Specification of Letters Patent.

Patented Dec. 5, 1911.

Application filed June 19, 1908. Serial No. 439,374.

To all whom it may concern:

Be it known that I, ELBERT H. CARROLL, a citizen of the United States, residing at Worcester, in the county of Worcester and 5 Commonwealth of Massachusetts, have invented a certain new and useful Improvement in Guide-Boxes for Rolling-Mills, of which the following is a specification, accompanied by drawings forming a part of 10 the same, in which—

Figure 1 is a front elevation of a rolling mill housing provided with a guide embodying my invention, and Fig. 2 is a section on line 2—2, Fig. 1, on an enlarged 15 scale.

Similar reference figures refer to similar parts in the different views.

My invention relates to a method of supporting the guide box of a rolling mill, by 20 which sufficient resistance to the strains of operation may be secured between the guide box and the supporting bar, and it consists in the construction and arrangement of parts as hereinafter described and pointed 25 out in the annexed claims.

Referring to the accompanying drawings, 1, 1, are the housings and 2, 2, a pair of rolls journaled therein.

3 is a guide box, supported on a bar 4, 30 which is attached to the front of the housings by bolts 5, 5, and vertically adjustable in slots 6, 6. Guide plates 7 and 8 may be used with the guide box, if desired. The bar 4 extends across the housing and is pro- 35 vided with longitudinal surfaces 9 and 10 to receive the guide box, upon which it is horizontally adjustable to bring it into alignment with the circumferential grooves 11 of the rolls. The guide box has at its outer 40 end a depending flange or apron 12, which is provided with a slot 13 for the reception of a bolt 14, having a head 15 horizontally adjustable along a longitudinal T-slot 16 in the bar 4, having a central opening 17 in the 45 upper side to allow the bolt 14 to be inserted in the slot 16.

The bearing surface 9 upon the bar 4 for the guide box 3 is located at the inner side of the bar, and the bearing surface 10 is 50 arranged to receive the lower edge of the depending apron 12. I thus provide bearing surfaces on the bar for the opposite sides of the guide box so that, in the case of a torque of the guide box, resistance to its

twisting movement will be provided upon 55 both sides of any possible horizontal axis of rotation. The upper surface of the guide bar 4 is also provided with an undercut or dovetailed shoulder 18, to receive a corresponding dovetailed shoulder 19 formed on 60 the under side of the guide box. The contacting surfaces of the shoulders 18 and 19 are arranged at an acute angle to the vertical, and thereby provide resistance to the twisting movement of the guide box upon 65 both sides of any possible vertical axis of rotation. The dovetailed shoulders are at an angle to the planes of the bearing surfaces 9 and 10 and when the guide box is placed in position with the dovetailed shoulders 70 18 and 19 engaging each other, as shown in Fig. 2, and with the bolt 14 inserted, the nut 20 is tightened to prevent the disengagement of the shoulders 18 and 19. The movement of the guide box, when the 75 nut 20 is tightened, is also approximately parallel with the planes of the bearing surfaces 9 and 10, so that the surfaces 9 and 10 are drawn more tightly into engagement by the movement of the guide box, controlled by the dovetailed shoulders 18 and 19, when the nut 20 is tightened. The bolt 80 14 may be made breakable under undue strain, thereby affording opportunity for the preservation of the guide box, which is 85 readily detached from the bar 4 by the removal of a single nut.

In the strains of ordinary operation, the guide box is held from lifting by the resistance afforded by the dovetailed shoulders 90 18 and 19, which, arranged at an acute angle to the vertical and extending the whole width of the guide box, prevent rotation about a vertical axis; and by the bearing surfaces 9 and 10 which, located at each 95 end of the guide box and equal in length to the width of said box, prevent its rotation about any intermediate horizontal axis and also prevent the disengagement of the shoulders 18 and 19 by any strains less than 100 the tensile strength of the bolt 14. As the surfaces 9 and 10 offer a positive resistance to the twist of the guide box as long as the dovetailed shoulders 18 and 19 are in engagement, the strain upon the bolt 14 is entirely longitudinal, all twisting strains being 105 taken by the bearing surfaces, which enables a comparatively light apron and small

bolt to be used, which, while of a strength sufficient to hold the guide box under the ordinary operation of the machine, will give way when subjected to the strain of an accident. As the flange 12 is drawn toward the bar by tightening the bolt 14, the bearing surfaces 9 and 10 serve to support the guide box, and the inclined shoulders 18 and 19 have a wedging effect to draw the guide box 10 against the surfaces 9 and 10. Pressure is, therefore, exerted between the guide box and all three of its contacting surfaces by the tightening of a single bolt 14.

I claim,

15 1. The combination of a rolling mill housing, a guide supporting bar, a guide box mounted on said bar, bearing surfaces on said guide box and said bar on opposite sides of said guide box in horizontal planes, 20 thereby preventing the rotation of said guide box about a horizontal axis, and also bearing surfaces on said guide box and said bar in a plane at an acute angle to the vertical, thereby preventing rotation of said 25 guide box about a vertical axis.

2. The combination of a rolling mill housing, a guide supporting bar, a guide box mounted on said bar, horizontal bearing surfaces on said guide box and said bar, 30 a longitudinal engaging shoulder at an acute angle to the vertical on said bar, a corresponding engaging shoulder on said guide box, and means for moving said guide box horizontally, thereby causing the wedging 35 action of said shoulders and the tighter engagement of said horizontal bearing surfaces.

3. The combination of a guide supporting bar having a shoulder, a guide box having 40 a corresponding shoulder arranged to be brought into engagement with the shoulder on said bar by a horizontal movement and to cause the approach of said guide box to said bar by said engagement, a bolt holding 45 said shoulders in engagement, and bearing surfaces between said bar and said guide box arranged to prevent during the engagement of said shoulders the rotation

of said guide box around any possible horizontal axis of rotation.

4. The combination of a rolling mill housing, a guide supporting bar, a guide box mounted on said bar, said guide box having a depending flange at its outer end, said guide bar having horizontal supporting surfaces for the lower end of said flange and the inner end of said guide box, and means arranged horizontally and passing through said flange for detachably attaching said guide box to said bar.

5. The combination of a rolling mill housing, a guide supporting bar, a guide box mounted on said bar, said guide box having a depending flange at its outer end, said guide bar having horizontal supporting surfaces for the lower end of said flange and the inner end of said guide box, a horizontal bolt passing through said flange with a head inserted in a slot in said bar, and a nut upon the outer side of said guide box.

6. A rolling mill having a guide box with a depending flange at its outer end, a guide bar with a horizontal supporting surface for the lower edge of said flange, a horizontal supporting surface for the inner end of said box, bearing surfaces at a slight angle from the vertical on said bar and guide box, and means for imparting a horizontal movement to said guide box to bring said angular bearing surfaces into engagement by which said guide box is caused to approach said bar.

7. A rolling mill having a guide box with a depending flange at its outer end, a guide bar having a supporting surface for the lower end of said flange, and interlocking surfaces on said guide box and said bar arranged at a slight angle from the vertical, whereby the horizontal movement of said guide box will draw said guide box nearer to said bar.

Dated this 17th day of June 1908.

ELBERT H. CARROLL.
